UNITED STATES PATENT OFFICE.

HANS WEIDE, OF NEW YORK, N. Y., ASSIGNOR OF ONE-HALF TO OSWALD LORENZ,
OF NEW YORK, N. Y.

LATCH.

1,137,819.

Specification of Letters Patent.

Patented May 4, 1915.

Application filed May 12, 1914. Serial No. 838,015.

To all whom it may concern:

Be it known that I, HANS WEIDE, a citizen of the United States, residing at New York, county of New York, and State of New York, have invented certain new and useful Improvements in Latches, fully described and represented in the following specification and the accompanying drawings, forming a part of the same.

10 This invention relates to an improved latch, adapted for use as a fastening device for boxes, trunks, bags, doors, and the like, the especial object of the invention being to provide a simple and efficient construction 15 in which the automatic fastening operation of the latch shall be assured without the use of weights or springs for controlling the parts.

A further object of the invention is to 20 prevent accidental unlatching.

For a full understanding of the invention, a detail description of a construction embodying the same will now be given in connection with the accompanying drawings 25 forming a part of this specification and illustrating the invention as applied in its preferred form to a box, and the features forming the invention then specifically pointed out in the claims.

30 In the drawings, Figure 1 is a vertical section through the box and cover in closed position, showing the latch in side elevation. Fig. 2 is a front elevation of Fig. 1. Fig. 3 is a view similar to Fig. 2, showing 35 the latch released and the box cover slightly raised. Fig. 4 is a cross section looking to the right on line 4—4 of Fig. 3. Fig. 5 is a view similar to Fig. 3, showing the parts in position of closing the box with the latch 40 about to be operated.

Referring to the drawings, A is the box with a hinged cover B to which the invention is shown as applied. The box A carries the latch plate 10 pivoted at 1, and having 45 its movement in both directions limited by stop 2, upon the box, shown as entering a slot in latch plate 10. The latch plate is provided with an upwardly extending arm 11, preferably bent outward slightly from the box, as shown, and this arm carries the 50 hook *a* forming the latch proper, which hook has an inclined surface 3 on its end for a purpose presently to be described. The latch proper *a* is in vertical line with the 55 pivot 1, in locking position, and at one side

of the pivot 1 the latch plate is provided with a surface 4 forming an abutment by engagement with which the latch plate 10 is rocked on its pivot 1 in latching direction and held in latched position, and the latch plate 10 is provided with a finger piece 5 for moving the latch plate in the other direction in unlatching.

The cover B carries the catch plate 12 having catch arm 13 on which is formed the 65 catch proper *b*, shown as a notch in the front edge of the catch arm, and the end of the arm is bent sidewise away from the latch arm 11, so as to form a trip 6 for engaging abutment 4 on the latch plate. The 70 arm 13 is preferably provided, also, with a shoulder 7 on its front edge, positioned to engage the incline 3 on the end of the latch *a*, as described hereafter.

The operation of the construction will be 75 understood from a brief description in connection with the drawings.

As shown in Figs. 1 and 2, the box is closed with the latch *a* engaged by catch *b*, the pull on attempted lifting of the cover 80 being substantially in line with the pivot 1, so that there is no tendency to unlatch, but the cover is locked against lifting. For unlatching the cover to open the box, the latch plate 10 is moved by finger piece 5 from the 85 position shown in Figs. 1 and 2, to that shown in Figs. 3 and 4, which withdraws the latch *a* from catch *b*. This rocking of the latch plate 10 to withdraw latch *a* necessitates the raising of the cover B at the same 90 time, as the trip 6 at the end of catch arm 13 is in engagement with abutment 4 of latch plate 10 at one side of the pivot 1. It is necessary, therefore, that the cover be lifted by hand simultaneously with the rocking of 95 the latch plate, to permit the latch plate 10 to be rocked on its pivot, two movements thus being necessary to open the box and any danger of accidental unlatching being thus avoided. If the weight of the cover or 100 other part to be moved be light, this co-action of abutment 4 and catch arm 13 may be used to lift the cover slightly by the rocking of latch plate 10, which may be found useful in some cases.

In closing the box, the latching is automatic and assured, as follows: The latch is expected to return after unlatching and opening the box, to the position shown in Fig. 5, in which case the shoulder 7 on 110

catch arm 13 below catch 3 will strike the incline 3 and rock the latch *a* to the right from the position shown in Fig. 5, so as to permit the straight portion of arm 13 to pass the latch and, as latch *a* comes opposite the catch *b*, the trip 6 at the end of arm 13 engages abutment 4 on the latch plate 10 and rocks the latch plate to move the latch *a* positively into latching position with catch *b*, as shown in Fig. 2. If latch plate 10, after unlatching, remains in the position shown in Fig. 3, until the closing of the box, the operation is the same, except that there is no throwing out of the latch *a* to permit catch arm 13 to pass it, but the trip 6 engages abutment 4 in the same manner to assure latching, when the latch *a* is opposite the catch *b*.

It will be understood that the invention is not to be limited to the exact form or arrangement of parts illustrated, but that many modifications may be made within the invention defined by the claims.

What is claimed is.

1. The combination of a pivoted latch plate and latch carried thereby, a catch co-acting with the latch, a catch plate carrying the catch and engaging the latch plate during the latching movement to move the latch into latching engagement with the catch and hold the latch in position to prevent unlatching except by the simultaneous rocking of the latch plate and movement of the catch plate, the engaging surfaces of the latch and catch in latched position being in line with the pivot and upon the line of movement of the parts away from each other, whereby separation of the parts without unlatching is resisted by direct pull upon the latch pivot.

2. The combination of a pivoted latch plate and hooked latch carried thereby, said latch having an incline, of a catch co-acting with the latch, a catch plate carrying the catch and engaging the incline on the latch to

rock the latch out of the path of the catch plate and engaging the latch plate during the latching movement to move the latch into latching engagement with the catch and hold the latch in position to prevent unlatching except by the simultaneous rocking of the latch plate and movement of the catch plate.

3. The combination with pivoted latch plate 10, having arm 11 carrying hooked latch *a* and abutment surface 4 at one side of the pivot, of catch arm 13 having catch opening *b*, and having an extension beyond the catch forming trip 6 engaging the abutment surface 4 to rock the latch plate into and hold it in latching position, the engaging surfaces of the latch and catch in latched position being in line with the pivot and upon the line of movement of the parts away from each other, whereby separation of the parts without unlatching is resisted by direct pull upon the latch pivot.

4. The combination with pivoted latch plate 10, having hooked latch *a* with end incline 3, arm 11 carrying hooked latch *a*, and abutment surface 4 at one side of the pivot, of catch arm 13 having catch opening *b* and having an extension beyond the catch engaging the incline 3 to rock the latch out of the path of the arm, and trip 6 engaging the abutment surface 4 to rock the latch plate into and hold it in latching position, the engaging surfaces of the latch and catch in latched position being in line with the pivot and upon the line of movement of the parts away from each other, whereby separation of the parts without unlatching is resisted by direct pull upon the latch pivot.

In testimony whereof I have hereunto set my hand in the presence of two subscribing witnesses.

HANS WEIDE.
